ATTORNEY

UNITED STATES PATENT OFFICE

JOHN ANDERSON, OF NEW YORK, N. Y.

SPRING MOTOR

Application filed March 29, 1929. Serial No. 350,855.

This invention relates to new and useful improvements in spring motors.

The invention has for an object the provision of a device of the class mentioned which is of simple durable construction, dependable in use and efficient in action, and which can be manufactured and sold at a reasonable cost.

The invention proposes the use of a plurality of energy storing means supported within a frame, and each means arranged to receive energy from a common driver pinion adapted for connection with sources capable of delivering the same and all arranged to individually, 15 partially simultaneously, or completely simultaneously deliver the energy to a common driven pinion adapted for connection with sources intended to receive the same. The energy storing means should be arranged 20 with a spiral spring capable of holding the desired energy.

For further comprehension of the invention, and of the objects and advantages thereof, reference will be had to the following description and accompanying drawings, 25 and to the appended claims in which the various novel features of the invention are more particularly set forth.

In the accompanying drawing forming a material part of this disclosure:—

Fig. 1 is an elevational view of a device constructed according to this invention.

Fig. 2 is a transverse vertical sectional view taken on the line 2—2 of Fig. 1.

Fig. 3 is a fragmentary sectional view of one of the spiral springs and associated parts used in the device.

Fig. 4 is a transverse sectional view taken on the line 4—4 of Fig. 3.

The reference numeral 10 indicates generally a base plate upon which a frame is firmly mounted, said frame consisting of three transverse parallel plates 11, 12 and 13 held in spaced relations by spacer bars 14.

A standard 15 is mounted upon the base 10 and supports a shaft 16 carrying a worm 17 meshing with a worm wheel 18 on a shaft 19 rotatively supported in the plate 11 of the said frame. A driver pinion 20 is secured upon the inner end of the shaft 19. A plural-

ity of energy storing means 21 are mounted between the plates 11 and 12, and are connected for receiving energy from the driver pinion 20, and delivering the energy to a driven pinion 60 on a shaft 22 rotatively mounted in the plates 12 and 13. The shaft 22 is provided with a pinion 23 on its outer end meshing with a pinion 24 on the shaft of energy receiving means 25 mounted on the said base 10.

Means for governing the steadiness of the power transmitted to the means 25 is provided, and consist of a pinion 26 fixed upon the shaft 22 and meshing with a gear 27 on a shaft 28 rotatively mounted in the plate 13 and in a bracket 30 secured upon the plate 12. A circular rack 31 is mounted upon the shaft 28 and has several apertures 32 engageable by a plunger 33 slidably mounted in a block 34 attached upon the bracket 30. Screws 35 threadedly engage in the block 34 and serve to hold the plunger 33 in a raised position free from any of the apertures 32 or in a position engaged in one of the said apertures.

Each of the energy storing means consists of a longitudinal shaft 36 rotatively supported between the plates 11 and 12 and provided with a ratchet wheel 37 firmly attached. A pawl 38 is mounted upon the plate 12 and engages against the ratchet wheel 37 for limiting rotation of the shaft 36 in one direction. A gear 39 is fixed upon the shaft 36 and meshes with the driver pinion 20. A hollow drum 40 is rotatively and slidably mounted upon the shaft 36, and at one end is formed with gear teeth 41 normally meshing with the said driven pinion 60. A spiral spring 42 is mounted within the hollow drum 40, and its outer end is fixed upon the inner periphery of the drum, while its inner end slidably engages upon a key 43 mounted in the shaft 36. The slideable engagement of the inner end of the spiral spring and the key is accomplished by a transverse pin 44 projecting from the key into elongated slot 45 formed in the spring.

The hollow drum 40 is provided with a grooved collar 46 at one of its ends, engaged by a fork 47 supported by a slideable bar 48 arranged for sliding in the plates 11 and 12.

One end of the bar 48 has a head 49 which limits its sliding in one direction and the other end has a handle 50 arranged for limiting the sliding in the opposite direction.

5 As shown in Fig. 1, the gear teeth 41 engage the driver pinion 22. The handle 50 may be drawn towards the right as indicated by dot and dash lines 51 for moving the drum 40 towards the right as indicated by dot and 10 dash lines 52 so that the gear teeth 41 are free from the pinion 60. In its new position the drum is held against rotation by a stop 53 projecting from the spacer bar 14.

In operation of the device each of the 15 handles 50 are moved to the left so that the gear teeth 41 of each of the hollow drums engage with the driven pinion 60. The screws 35 are then loosened and the plunger 33 engaged in one of the apertures 32 for indirectly locking the driven pinion 60 against rotation. Power may then be stored in the 20 energy storing means 21 by causing the power to rotate the shaft 16 which rotation is transmitted to the driver pinion 20 and all 25 of the shafts 36. Rotation of the shafts 36 cause a winding of all of the spiral springs 42. Next the supply of power may be discontinued and the shaft 16 locked against rotation by means not shown on the drawing.

30 The power contained in the energy storing means may be used from each of the storing means individually, partially simultaneously, or completely simultaneously as desired. When the plunger 33 is drawn out 35 of the aperture 32, power from the spiral springs will be delivered to the driven pinion 60 and to a suitable receiving means such as the generator 25. In this condition all 40 the energy storing means 21 act simultaneously. While the plunger was engaged within one of the apertures 32, one or more of the handles 50 could have been moved towards the right for disconnecting one or more of the energy storing means from the driven 45 pinion. The stops 53 serve to hold the power within the storing means in the moved position thereof. A releasing of the circular rack 31 by a withdrawing of the plunger, permits the energy storing means connected 50 with the driven pinion to transfer its energy to the means 25.

While I have shown and described the preferred embodiment of my invention, it is to be understood that I do not limit myself to the precise construction herein disclosed and the right is reserved to all changes and modifications coming within the scope of the invention as defined in the appended claims.

Having thus described my invention, what 55 I claim as new, and desire to secure by United States Letters Patent is:

1. A device of the class described, comprising a frame, a plurality of shafts therein, a drum rotative on each shaft, and formed 60 with gear teeth, spiral springs within the

drums, fixedly attached on the drums and longitudinally slideable on the shafts, means for restraining rotation of the shaft in one direction, gears on the shaft meshing with a driver pinion, a driven pinion mounted in the frame and meshing with the gear teeth of the drums, means for sliding the drums to move their teeth out of mesh, and means for holding the drums against rotation in the said moved positions.

2. A device of the class described, comprising a frame, a plurality of shafts therein, a drum rotative on each shaft, and formed with gear teeth, spiral springs within the drums, fixedly attached on the drums and longitudinally slideable on the shafts, means for restraining rotation of the shaft in one direction, gears on the shaft meshing with a driver pinion, a driven pinion mounted in the frame and meshing with the gear teeth of the drums, means for sliding the drums to move their teeth out of mesh, and means for holding the drums against rotation in the said moved positions, the latter means consisting of stops engageable in the gear teeth and projecting from spacer bars constituting elements of the frame.

In testimony whereof I have affixed my signature.

JOHN ANDERSON.
